UNITED STATES PATENT OFFICE.

BAXTER P. HAMILTON, OF BROOKLYN, NEW YORK, ASSIGNOR TO AMERICAN TELEPHONE AND TELEGRAPH COMPANY, A CORPORATION OF NEW YORK.

CARRIER TELEGRAPH CIRCUITS.

Application filed October 21, 1920. Serial No. 418,486.

To all whom it may concern:

Be it known that I, BAXTER P. HAMILTON, residing at Brooklyn, in the county of Kings and State of New York, have invented certain Improvements in Carrier Telegraph Circuits, of which the following is a specification.

This invention relates to signaling systems, and more particularly to systems in which telegraph signals are transmitted by means of carrier currents.

One of the objects of this invention is to provide a repeater apparatus for carrier telegraph systems, said repeater apparatus being so arranged that a local subscriber's circuit or loop may be associated therewith for the purpose of transmitting signals to and receiving signals from the repeater apparatus.

Another object of the invention is to provide means whereby a subscriber's loop will be associated with the repeater apparatus and repeater telegraph system in such a manner that the loop will operate for the transmission of signals to and from the repeater upon a half duplex basis.

Another object of the invention is to provide means whereby a subscriber's loop will be associated with the repeater apparatus and repeater telegraph system in such a manner that the loop will operate for the transmission of signals to and from the repeater upon a full duplex basis.

Other and further objects of the invention will be clear from the following description when read in connection with the accompanying drawings, Figures 1, 2, and 3 of which illustrate circuit diagrams embodying a number of different forms of the invention, and Figs. 4 and 5 of which show the detailed circuit arrangement of the carrier transmitting and receiving apparatus used in connection with the repeater.

Referring to Fig. 1, MLE and MLW 45 designate transmission line sections over which carrier currents may be transmitted. A transmitting circuit TLE and a receiving circuit RLE are associated with the main line section MLE through a balanced transformer 10', an artificial line and network, MNE, being provided for balancing the main line circuit. For the same purpose transmitting circuit TLW and receiving circuit RLW are associated with the main line 50 section MLW through a balanced transformer 10 through a balanced transformer 10'.

and balancing network MNW. A plurality of carrier channels may be associated with each of the transmitting and receiving circuits above described for multiplex work. For purposes of illustration, a single channel 60 is shown associated with each circuit; thus a transmitting channel associated with the circuit TLE is illustrated as comprising a transmitting amplifier TAE, to which an oscillator GE may be connected under certain circumstances as more fully explained hereinafter. A similar transmitting amplifier TAW and oscillator GW are shown as being associated with the circuit RLW. The amplifying arrangements above described 70 may be of any well-known form, such as, for example, vacuum tube amplifiers. The generators may also be of any known character adapted to generate a carrier frequency, but are preferably vacuum tube oscillators. A 75 typical arrangement of oscillator and amplifier is illustrated in Fig. 4. In practice, when the apparatus is used as a through repeater, the generator is unnecessary, and will be disconnected from the amplifier at 80 the points indicated by the crosses. The filament of the amplifying tube will, in such case, have its circuit completed to battery directly through a resistance (indicated in dotted lines), which is equal to the resistance 85 of the filament of the oscillating tube GE.

A receiving channel, comprising a receiving amplifier RAE, detector DE, and receiving relay RE, is shown as being associated with the receiving circuit RLE. A 90 similar receiving arrangement, comprising an amplifier RAW, detector DW, and receiving relay RW, is shown associated with the receiving circuit RLW. The amplifiers RAE and RAW may be of any well-known 95 type: for example, vacuum tube amplifiers having the construction illustrated in Fig. 5. The detectors, likewise, may be of any well-known character, but are preferably vacuum tube detectors, such as illustrated at DE in 100 Fig. 5. The receiving relay RE is preferably a polar relay, and, in order that it may operate upon an alternating current basis, the polar relay is connected to the out-put circuit of the detector through a transformer 105 11, as indicated in Fig. 5.

In order that the transmitting and receiving channels may be utilized for through repeating, the transmitting channel of each line is directly connected to the receiving 110

channel of the opposite line; for example, a conductor 12 interconnects the out-put circuit of the receiving amplifier RAW, and the in-put circuit of the transmitting amplifier TAE; likewise, a conductor 13 directly connects the out-put circuit of the receiving amplifier RAE and the in-put circuit of the transmitting amplifier TAE. The manner in which the circuit 12 is associated with the in-put circuit of the amplifier TAE is indicated in Fig. 4, and the manner in which the circuit 12 is associated with the out-put circuit of the receiving amplifier RAW will be understood from inspection of the connection of the circuit 13 to the receiving amplifier RAE, illustrated in Fig. 5. When the amplifiers of the transmitting and receiving channels are thus connected, the amplifier of the receiving channel works directly into the amplifier of the transmitting channel, and the carrier signals will be repeated at carrier frequency.

In order that a local subscriber's loop L may be associated with the repeater apparatus for transmitting and receiving signals, a jack J is provided, in which the plug P of the loop may be inserted. The loop connection leading from jack J is balanced by means of a balancing circuit N, and three polar relays, PE, PW, and PW', are so associated with the loop that one winding of each relay is included in the loop connection and the other winding of each relay is included in the balancing connection, the several windings of the relay being mutually connected in series. The polar relays PE and PW are transmitting relays, and control the circuits of sounders SE and SW, as well as short circuit connections 14 and 15 respectively, whereby the connections 12 and 13 may be short-circuited to prevent the transmission to the transmitting amplifiers of the carrier frequency normally passing over the through repeating channels. One end of the loop is normally connected to a battery lead of one polarity, while the junction point 16 of the windings in the loop and balancing circuits is connected through a battery lead of the opposite polarity over the normal contact of the relay PW' and the normal contact of the receiving relays RW and RE in series. The alternate contacts of the receiving relays are connected to battery leads of the opposite sign to that connected with the point 16. The armature of the relay PW' is arranged so that when said relay is operated in response to the transmission of a signal from the loop the normal connection of battery over the contact of the receiving relays RW and RE is opened and the normal battery connection is established directly over the armature of the relay PW' independently of either receiving relay.

Further details of the apparatus will be

clear from the description of the operation, which is as follows: Normally, when signals are not transmitted, a carrier frequency incoming from the line MLE passes through the amplifier RAE and over the connection 13 to the amplifier TAW, and thence to the main line section MLW; similarly, a carrier frequency passes from west to east from the main line section MLW through the amplifier RAW, over the circuit 12 to the amplifier TAE, and thence to the main line section MLE. Signals may be transmitted in either direction by interrupting the carrier frequency transmitted in the desired direction. Since the circuit is intended to operate on a half duplex basis, however, signals will in practice be transmitted over only one of the paths above described at a time. If signals are transmitted over the first mentioned path by interrupting the carrier frequency, the detector DE will respond to the interruptions, and the polarized relay RE will shift its armature from negative battery to positive battery. When the armature of the relay RE was connected to negative battery, since the other end of the loop was connected to positive battery, a current flow through the loop windings of the polar relays occurred which was twice as great as the current flow passing through the balancing windings which were connected directly to ground. The effect due to the current flow in the upper windings, therefore, predominates, and the pull asserted is in such a direction as to hold the armatures of said relays in the normal position. When the armature of the receiving relay RE is shifted to positive battery, however, the battery connections at the opposite ends of the loop are opposing, consequently no current flows through the loop, and the sounders included therein (not shown) release their armatures. The upper windings of the polar relays PE, PW, and PW' are also deenergized, and current flows only through the lower windings of said relays. The current flow is reversed, however, from that normally flowing and consequently tends to hold the armatures of the relays against their normal contact, so that the transmitting relay PE is ineffective to transmit the signal back to the line MLE, from which it came, and the relay PW is ineffective to short-circuit the connection 18, over which the carrier signals are being transmitted from one line section to the other.

In a similar manner, if signals from the line MLW are transmitted over the conductor 12 to the line section MLE by interrupting the normally transmitted carrier frequency, the receiving relay RW responds and connects positive battery to the point 16, so that no current flows through the loop and the sounders therein release their arma-

tures. The effect upon the polar relays PW and PW' is the same as that already described.

If it is desired to transmit signals from the loop to the two line sections, the loop may be interrupted by means of a sending key (not shown). Each time the loop is opened, the current flow through the upper windings of the relays PE, PW, and PW' ceases. The current flow through the lower windings, however, is in the normal direction, and the lower windings therefore become effective to shift the armatures of said relays to their alternate contacts. The armatures of relays PE and PW open the circuits of the sounders SE and SW and close short circuit connections 14 and 15, whereby the carrier frequencies normally transmitted from each line section to the other are diverted to ground, and thus interrupted so far as transmission to the other transmission line is concerned. The signals originating in the loop L will therefore be transmitted to each line section as interruptions in the carrier frequency. The relay PW', in shifting its armature to its alternate contact, connects negative battery to the point 16 directly over said contact, and independently of the armatures of the receiving relays RE and RW, so that said relays are ineffective to transmit signals to the loop while signals are being transmitted from the loop.

A break signal may be transmitted from the loop when signals are being received from either line section by holding open the loop by means of a sending key. The opening of the loop causes the closing of the short circuit connections 14 and 15 in the manner previously described, and therefore the carrier frequency transmitted from each line section to the other will be interrupted during the continuance of the break signal. The effect of the break signal at the sending station, which may be assumed to be similar to that illustrated in Fig. 1, may be understood from the effect of a break signal received by the loop L. If a break signal comes in from the line section MLW, the receiving relay RW shifts its armature and connects positive battery to the point 16. As soon as the armature of the relay PW' assumes its normal position, which will occur when the loop is closed by the transmission of the space signal, no current flow occurs through the upper windings of the relays PE, PW and PW', and the current flow through the lower windings is in such a direction as to hold their armatures against their normal contacts. The operator, in opening and closing the loop for further transmission of signals, will observe that the local sounder does not follow the sending key, and will therefore be apprised that a break signal has been received.

Fig. 2 illustrates a similar arrangement

adapted to be operated upon a full duplex basis. The through repeater connections are the same as in Fig. 1. In this instance, however, signals will in practice be simultaneously transmitted in both directions by interrupting the normally transmitted carrier frequency. This involves the provision of an additional subscriber's loop, so that signals may be received and transmitted simultaneously from the subscriber's station. One of the loops LE is arranged to receive through signals transmitted from east to west and to transmit signals from west to east. The other subscriber's loop LW is arranged to receive signals transmitted from west to east and to transmit signals from east to west. Loop LE is balanced by an artificial line and network NE, and the loop LW by a similar network NW. The windings of polar relays PW and PW' are associated with the loop LW and the balancing circuit NW in a manner similar to that shown in Fig. 1, but in this instance the normal battery connection to the point 16 extends only over the contact of the receiving relay RW, and is entirely independent of the receiving relay RE. Polar relays PE and PE' are associated with the loop LE, said relays having their upper windings in the loop and the lower windings in the balancing circuit MNE. A connection extends from the junction point 17 of the polar relay windings over the normal contact of the armature of the polar relay PE', and over the normal contact of the receiving relay RE to negative battery. Positive battery is connected to the alternate contact of the receiving relay RE, and the connection is such that when the armature of the polar relay PE' is shifted from its normal position the battery connections controlled by the relay RE are opened, and an independent connection to negative battery is closed.

The operation is as follows: Signals will be transmitted over the through repeater channel from the line section MLE to the line section MLW as described in connection with Fig. 1. Each time the frequency is interrupted the receiving relay RE responds and shifts its armature from negative battery to positive battery, so that the battery connections at each end of the loop LE are mutually opposing. No current flows through the loop, therefore, and sounders in the loop respond. The upper windings of the polar relays PE and PE' are de-energized but the current flow through the lower windings is in such a direction as to hold the armatures of said relays against their normal contacts, and the signal is thereby prevented from being transmitted back to the line section MLE. Signals may be transmitted from the loop LE by opening and closing the same. Each time the

loop is opened, the upper windings of the relays PE and PE' are deenergized, and the lower windings become effective to shift their armatures to their alternate contacts. 5 The armature of the relay PE, when shifted, closes short circuit connections 14, whereby the carrier frequently transmitted from west to east over the circuit 12 may be interrupted, and signals transmitted over 10 the line sections MLE. The armature of the polar relay PE' is shifted at the same time, and opens the battery circuit controlled by the receiving relay RE, and connects the negative battery to point 17 independent of the said relay. The receiving 15 relay is therefore ineffective to transmit signals to the loop when signals are being sent from the loop.

The operation of the loop LW with respect to receiving signals transmitted from west to east and with respect to the transmission of signals from the loop west will be readily understood from the operations above. The details of this feature of the 25 operation need not, therefore, be further considered.

It will be seen from the description of Fig. 2 that while the carrier channels are arranged to be operated full duplex, each of 30 the subscribers' loops LE and LW is operated on a half duplex basis, as the same loop is used both for transmitting and receiving, and the two operations cannot take place simultaneously.

35 Fig. 3 illustrates an arrangement, however, in which not only the carrier channels are operated full duplex, but the loops are also arranged to be operated full duplex. This involves the provision of four loops, 40 the loop RLE receiving signals transmitted from east to west, the loop RLW receiving signals transmitted from west to east, the loop TLE transmitting signals east, and the loop TLW transmitting signals west. As 45 an additional feature, a switch SS is provided whereby the transmitting loops TLE and TLW may be connected together, so that signals may be transmitted both east and west from the loop by operating a single key. The receiving relays RE and RW are arranged to merely open and close the loops RLE and RLW respectively. In the 50 normal arrangement of the loops TLE and TLW with the contacts of the switch SS arranged as indicated, balancing circuits TNE and TNW are provided for the two loops, said balancing circuits being so arranged that, due to the potential of the batteries connected to the junction points 16 55 and 17 of the loops and balancing circuits, a greater current flows through the loop than flows through the balancing circuit.

The windings of polar relays PE and PW are arranged so that the upper windings are in the loop circuits and the lower wind-

ings in the balancing circuits. The greater current flow through the upper windings overcomes the effect of the lower windings, so that under normal conditions the upper windings are effective to hold the armatures 70 of the relays against their normal contacts. The repeater connections for through transmission are the same as already described, and the armatures of the polar relays PE and PW are arranged to close short circuit 75 connections 14 and 15 in the same manner as Figs. 1 and 2. The battery connections to the points 16 and 17 are of opposite sign, so that if the loops TLE and TLW be clearly connected by means of the switch SS, a greater current will flow through the serial loop thus obtained than through the balancing circuits, due to the fact that the batteries are series aiding. With the circuit 80 in this condition, signals may be simultaneously transmitted from the loop both to the east and to the west by operating either the key KE or the key KW.

The operation is as follows: Signals transmitted from the line section MLE to the line section MLW through the repeater connection 13 will operate through the detector DE to cause the receiving relay RE to respond, thereby opening and closing the loop circuit RLE so that the receiving sounder RSE records the signal. In a similar manner carrier signals transmitted from the line section MLW to the line section MLE over the repeater connection 12 cause the receiving relay RW to respond, thereby opening and closing the loop RLW so that the receiving sounder RSW records the signals. 90

With the switch SS in normal position as shown in the drawing, loops TLE and TLW are both grounded and signals may be simultaneously sent from each loop by manipulating keys KE and KW. Each time the loop TLE is opened, the upper winding of the polar relay PE is deenergized, and the lower winding thereof becomes effective to shift its armature to close the short circuit connection 14, thereby interrupting the frequency transmitted over the conductor 12 to the line section MLW. Similarly, the opening of the loop TLW deenergizes the upper winding of the polar relay PW, so that the lower winding becomes effective to shift the armature of the relay and close the short circuit connection 15, thereby interrupting the carrier frequency normally transmitted over the circuit 13 to the main line section MLW. 105 110 115

If the switch SS is shifted to connect the loops TLE and TLW in series, signals may be simultaneously transmitted both east and west by the same key. If the serial loop thus formed is opened by the key KE, for example, the upper windings of both relays PE and PW are deenergized, and the 120 125 130

lower windings become effective to shift the armature of both relays, thereby interrupting the normal carrier frequency transmitted in each direction from one line section to the other. Consequently, the signals from the serial loop are transmitted to the line section MLE as interruptions of the carrier frequency transmitted from MLW to MLE, while the similar interruptions of the loop 10 are transmitted to the line MLW as interruptions of the normal carrier frequency transmitted from the line section MLE and MLW.

The oscillators GE and GW already described are provided in connection with the arrangements of each of the transmitting channels in order that, if it is desired to operate the loops and associated carrier apparatus as terminals station for each line 20 section, the repeater connections 12 and 13 may be opened and the oscillator connections to the transmitting amplifiers closed. The normal carrier frequency supplied to each line section will therefore be provided by the oscillator, and this frequency may be interrupted by the short circuit connections 14 and 15, which will extend over a portion of the conductors 12 and 13 to the grid circuits of the transmitting amplifiers. 30 The operations of sending and receiving with the circuits thus altered will be obvious from the operations already described, and need not be further discussed.

It will be obvious that the general principles herein described may be embodied in many other organizations widely different from those illustrated, without departing from the spirit of the invention as defined in the following claims.

40 What is claimed is:

1. In a signaling system, two transmission line sections over which carrier currents may be transmitted, a carrier repeater arrangement for interconnecting said sections, said repeater arrangement comprising carrier transmitting channels and carrier receiving channels associated with each line section, means for interconnecting the carrier receiving channel of each line section 45 with the carrier transmitting channel of the opposite line section, a low frequency telegraph circuit, a balancing circuit therefor, a polar relay arrangement having windings in said telegraph circuit and balancing circuit, means whereby said polar relay may control the transmission of carrier currents from at least one of said carrier transmitting channels to the corresponding line section, a receiving relay associated with 50 at least one of said carrier receiving channels, a source of current connected to the junction point of the windings of said polar relay arrangement over one contact of said receiving relay, a second source connected 55

to the opposite end of said telegraph circuit, said second source being so poled as to be mutually aiding with respect to said first source, a third source connected to another contact of said receiving relay, said third source being so poled that when the 60 armature of the receiving relay is shifted, mutually opposing sources will be connected to said telegraph circuit, and means whereby when said polar relay arrangement is operated in response to signals received over 65 said telegraph circuit, said first mentioned source will be connected to the junction point of the windings of said polar relay arrangement independently of said receiving 70 relay.

2. In a signaling system, two transmission line sections over which carrier currents may be transmitted, a carrier repeater arrangement for interconnecting the ends of said line sections, said carrier repeater arrangement comprising carrier transmitting channels and carrier receiving channels associated with each line section, means for interconnecting the carrier receiving channel associated with each line section with the carrier transmitting channel associated with the opposite line section, a low frequency 80 telegraph circuit, a balancing circuit therefor, a polar relay arrangement having windings in said telegraph circuit and said balancing circuit, said polar relay arrangement 85 controlling the transmission of carrier currents from both transmitting channels to the corresponding line sections, receiving relays associated with each carrier receiving channel, a source of current connected with the junction point of the windings of said polar relay arrangement over a contact of each of said receiving relays in series, a second source of current connected to the opposite end of said telegraph circuit, said second source of current being so poled as to be mutually aiding with respect to 90 said first source, and a third source connected to other contacts of each of said receiving relays, said third source being so poled that when the armature of either receiving 95 relay is shifted, mutually opposed sources are connected to opposite ends of said telegraph circuit.

3. In a signaling system, two transmission line sections over which carrier currents may be transmitted, a carrier repeater arrangement for interconnecting the ends of said line sections, said carrier repeater arrangement comprising carrier transmitting and carrier receiving channels associated with each line section, means for connecting the carrier receiving channel associated with each line section with the carrier transmitting channel associated with the opposite line section, a low frequency telegraph circuit, a balancing circuit therefor, a polar 100

relay arrangement having windings in said telegraph circuit and said balancing circuit, said polar relay arrangement controlling the transmission of carrier currents from both transmitting channels to the corresponding line sections, receiving relays associated with each carrier receiving channel, a source of current connected with the junction point of the windings of said polar relay arrangement over a contact of each of said receiving relays in series, a second source of current connected to the opposite end of said telegraph circuit, said second source of current being so poled as to be mutually aiding with respect to said first source, and a third source connected to other contacts of each of said receiving relays, said third source being so poled that when the armature of either receiving relay is shifted, mutually opposed sources are connected to opposite ends of said telegraph circuit, and means controlled by said polar relay arrangement whereby said first mentioned source may be connected to the junction point of the windings of said polar relay arrangement independently of the contacts of either receiving relay.

4. In a signaling system, two transmission line sections over which carrier currents may be transmitted, a carrier repeater arrangement for interconnecting the ends of said line sections, said repeater arrangement comprising carrier transmitting channels and carrier receiving channels associated with each line section, means for interconnecting the carrier receiving channel of each line section with the carrier transmitting channel of the opposite line section, a low frequency telegraph loop circuit, a pair of transmitting polar relays each having loop windings and balancing windings, the loop windings being mutually in series in said loop circuit, said polar relays controlling the transmission of carrier currents from the transmitting channels to the corresponding line sections, mutually aiding sources of current connected to opposite ends of said loop circuit, and means associated with said loop whereby both polar transmitting relays may be oper-

ated jointly to transmit signals from said loop over both line sections simultaneously.

5. In a signaling system, a pair of transmission line sections over which carrier currents may be transmitted, a carrier repeater apparatus for interconnecting the ends of said line sections, said repeater apparatus comprising carrier transmitting channels and carrier receiving channels associated with each line section, means for interconnecting the carrier receiving channel of each line section with the carrier transmitting channel of the opposite line section, a low frequency telegraph circuit, a balancing circuit therefor, a pair of polar relays each having windings in the telegraph circuit and in the balancing circuit, the windings of said polar relays in said telegraph circuit being mutually in series and the windings of said polar relays in the balancing circuit being mutually in series, means operated by at least one of said polar relays for controlling the transmission of carrier currents from one of said carrier transmitter channels to a line section, a receiving relay associated with at least one of said carrier receiving channels, a source of current connected to the junction point of the windings of said polar relays over one contact of said receiving relay, a second source of current connected to the opposite end of said telegraph circuit, said second source being so poled as to be mutually aiding with respect to the first source, and a third source connected to another contact of said receiving relay, said third source being of opposite polarity from said first source, and means controlled by one of said polar relays whereby when signals are transmitted to the polar relays over said low frequency telegraph circuit, said first mentioned source will be connected to the junction point of the windings of said relays independently of said receiving relay.

In testimony whereof, I have signed my name to this specification this 18th day of 95 October, 1920.

BAXTER P. HAMILTON.
